UNITED STATES PATENT OFFICE.

JOSIAH BAKER GATHRIGHT, OF LOUISVILLE, KENTUCKY.

CAR-FENDER.

1,262,322.

Specification of Letters Patent.

Patented Apr. 9, 1918.

Application filed January 14, 1918. Serial No. 211,856.

To all whom it may concern:

Be it known that I, JOSIAH BAKER GATHRIGHT, a citizen of the United States, residing at Louisville, in the county of Jefferson and State of Kentucky, have invented certain new and useful Improvements in Car-Fenders, of which the following is a specification.

This invention relates to fenders for cars and it has for one of its more important objects the provisions of an improved device of this nature constructed in such manner that a person caught within the fender will be automatically swung to a position of safety and deposited outside of the line of travel of the car with a minimum of shock and jar.

Further important objects of the invention are to provide a fender of the character above set forth which will be of simple and durable construction, may be quickly and easily attached to cars already in use, will not be subject to annoying rattling in travel and will be capable of automatic release to perform its functions under the weight of the person caught therein.

Other objects and advantages of the invention will be apparent from the following description and accompanying drawing setting forth and illustrating in detail the preferred embodiment of the invention.

In the drawing,

Figure 1 is a horizontal sectional view of a part of a street car with the fender in plan view;

Fig. 2 is a side elevation of the fender;

Fig. 3 is a partial front view of the car illustrating a detent hereinafter described, and

Fig. 4 is a sectional view through one of the elements of said detent;

Referring to the drawing, A designates the front platform of a street car to which my improved fender is applied. The fender comprises a suitable netting 5 that is supported within an appropriate frame which preferably comprises a transverse top bar 6, vertical side posts 7 and 8, a transverse front bar 9 which may have a soft covering 10, as of rubber, if desired, and side frame members 11 which extend from the front bar 9, to, and form continuations of the lower ends of the side posts 7 and 8. The side post 7 is journaled in upper and lower bearing brackets 12 and 13 carried by the platform A, to thereby render it possible for the fender as a whole to swing bodily from the full line position to the dotted line position, illustrated in Fig. 1. This swinging movement is brought about by the action of a coiled spring 14 which is wound about the post 7 and has one of its ends secured to the bracket 12 at 14^a and its other end secured to the post 7 at 14^b. A stay chain 15 is connected at 16 and 17 to the fender and the platform A, respectively, and limits the swinging movement of the fender.

Any suitable detent releasable under the weight of a person caught in the fender may be employed. One form of such detent is illustrated in the drawing and comprises a bracket 18 which is carried by the platform A and has a socket 19 formed in its under face, with which an upstanding projection 20 of the side post 8 is adapted to have engagement.

In operation the fender is swung against the tension of the spring 14 to the full line position illustrated in Fig. 1 and the projection 20 sprung into the socket 19. There is sufficient give to the parts to permit this to be done. It is designed to have the parts so arranged that it will take considerable effort to spring the projection 20 into the socket 19 so that there will be no likelihood of the parts becoming disengaged during the ordinary jolt and jar of the car in travel. If, however, a heavy object, such as a person's body, is caught within the fender, the weight of such object will depress the post 8 sufficiently to free the projection 20 from the socket 19, whereupon the spring 14 will throw the fender from the full line position, illustrated in Fig. 1 to the dotted line position illustrated in said figure, thereby moving the person bodily from the track and beyond the line of travel of the car. The sudden checking of the movement of the fender by the chain 15 will result in the person being thrown from the fender upon the ground but at a safe distance beyond the line of travel of the car.

It is particularly to be noted that in the present invention the fender extends entirely across the front of the car and is of such a nature that the person to be removed from the track must actually be in contact therewith before the fender is released, and further, that the fender is of such a nature as actually to carry the person from the track instead of merely pushing the person from the track. These several features are

of great importance and utility, for the reasons: First, there is no likelihood of a person's feet being caught and crushed between the lower part of the fender and the ground, 5 as would be the case if the fender was constructed to merely push the person from the track instead of bodily carrying the person from the track. Second: the person being already in actual contact with the fender 10 before the fender begins its swinging movement there is no initial impact between the fender and the body of the person, such as would tend to break a person's limbs; and third, the person when finally deposited to 15 one side of the track is lying in a recumbent position so that he or she will merely roll upon the ground, it being apparent that the danger of injury under these circumstances will be much less than if a person were 20 thrown from a standing position.

While the elements herein shown and described are well adapted to serve the purposes for which they are intended it is to be understood that the construction shown in 25 the accompanying drawing and herein particularly set forth is merely exemplary since many ways of mounting the fender with respect to the car and of arranging the spring to actuate the same will readily suggest 30 themselves to those skilled in the art. It is therefore to be understood that the invention is not limited to the precise construction shown but that it includes within its purview whatever changes fairly come within 35 the spirit of the appended claims.

Having described my invention what I claim is:—

1. In combination, a car fender comprising a rigid frame, said fender being of such 40 length as to extend entirely across the track, means engaged with said fender at one side thereof for bodily swinging the fender in a substantially horizontal plane across the track, a detent at the opposite side of the fender for holding it against movement under the action of said means, and means for 45 automatically releasing the fender from the detent when an obstacle is caught by the fender.
- 50 2. A fender comprising a rigid frame, said fender being of such length as to extend entirely across the track, means engaged with said fender at one side thereof for bodily swinging the fender in a substan-

tially horizontal plane across the track, and 55 a detent for holding the fender against the action of said means, said detent being releasable under the weight of a person caught within the fender.

3. In combination, a fender comprising a 60 rigid frame, said fender being of such length as to extend entirely across the track, spring means engaged with said fender at one side thereof and tending to swing the same across the track and a detent at the opposite 65 side of the fender releasable under the weight of a person caught within the fender.

4. In combination, a fender comprising a rigid frame, said fender being of such length as to extend entirely across the track, 70 bearing members in which said fender is journaled to swing from one of its sides, spring means engaged with the fender and the bearing member and tending to swing said fender, and a detent at the opposite 75 side of the fender releasable under the weight of a person caught within the fender.

5. A fender comprising a rigid frame, said fender being of such length as to extend across the track, spring means engaged 80 with said fender and tending to swing the same across the track, a detent for resisting the movement of the spring means and a stay member for limiting the movement of the same.

6. A fender comprising a rigid frame, said fender being of such length as to extend entirely across the track, spring means normally tending to swing said fender and a detent for said fender, comprising a socketed element and a projection upon the fender engaging with said socketed element.

7. A fender comprising a rigid frame, said fender being of such length as to extend entirely across the track, spring means tending to swing the fender and a detent for the fender, comprising interengaging elements, one of which is adapted to be moved out of the path of the other under the weight 100 of a person in the fender.

In testimony whereof I affix my signature in the presence of two witnesses.

JOSIAH BAKER GATHRIGHT.
